UNITED STATES PATENT OFFICE.

ISRAEL DONALD BOYER AND EDITH E. L. BOYER, OF DAYTON, OHIO,
ASSIGNORS TO CLARK & BOYER, OF SAME PLACE.

LOCOMOTIVE TOY.

SPECIFICATION forming part of Letters Patent No. 593,174, dated November 2, 1897.

Application filed December 11, 1896. Serial No. 615,422. (No model.)

To all whom it may concern:

Be it known that we, ISRAEL DONALD BOYER and EDITH E. L. BOYER, citizens of the United States, residing at Dayton, in the 5 county of Montgomery and State of Ohio, have invented a new and useful Improvement in Locomotive Toys, of which improvement the following is a specification.

The object of our invention is to provide a 10 toy of this class which shall be free from the objections inherent in spring-driven toys, which shall be simple in construction, cheap to manufacture, easy to operate, and not liable to get out of order.

15 It consists of a four-wheeled truck and a heavy inertia-wheel, the latter being fixed to a shaft which has its sole bearings on the peripheries of the four running-wheels of the truck, so that any motion imparted to the inertia-wheel will be transmitted through its 20 shaft to the four running-wheels of the truck, causing the truck to move over the floor, or, vice versa, any motion given to the truck will be transmitted through its four running-wheels to the shaft of the inertia-wheel.

25 Referring to the drawings, Figure 1 is a side elevation of the toy complete. Fig. 2 is an end elevation of the same. Fig. 3 is a plan of the same. Fig. 4 is an end elevation of a modified construction. Fig. 5 is a side elevation of the frame alone. Fig. 6 is an end elevation of the same. Fig. 7 is a plan of the same. Fig. 8 is a view of one of the axles with the 30 two wheels in section. Fig. 9 is an elevation and plan of the locking-bar or draft-rod.

The frame F is shown by itself in Figs. 5, 6, and 7. It is a single piece of cast-iron having two notches *b b* on the under edge of each side. These notches form bearings for the 40 ends of the axles. In the center of the upper edge of each end is a depression *d*. There is also a vertical groove *g* in the outer face of each end of the frame. The wheels upon one of the axles are closer together than those 45 upon the other axle, sufficiently so to enable the two pairs of wheels to overlap when they are mounted in the frame. It is immaterial whether the wheels be loose or tight upon the axles.

The various parts are assembled as follows: 50 The axles, with their wheels upon them, are placed in proper position on the floor and the frame let down upon them, the notches *b b* of the frame slipping over the ends of the axles outside the wheels. By suitable manipulation the rod R is then slipped over one 55 end of the frame, under the two axles, and over the other end of the frame. The hooks are then turned downward and gravity will keep them so, the rod lying in the two grooves 60 *d d* in the frame and serving to lock all the parts of the truck together. By turning the hooks upward the rod may be easily removed again and the whole truck taken to pieces.

As the most suitable motor we employ the 65 double-wheeled top illustrated in Fig. 2 of our application for patent on an improvement in spinning-tops filed December 7, 1896, Serial No. 614,824. This top is shown in position on the truck in Figs. 1, 2, and 3 of this 70 application. It consists, essentially, of two heavy-rimmed wheels fixed to a spindle near its ends and having an open handle loosely mounted on the spindle between them. A string permanently attached to the spindle 75 within the open handle constitutes the means for imparting velocity to the heavy wheels. The top is held by the handle in one hand, while velocity is imparted with the other by pulling the string. The live top or "motor," 80 as we may now call it, is laid with the two projecting ends of its shaft resting in the angles formed by the peripheries of the two pairs of overlapping running-wheels of the truck. Thus the whole weight of the top comes upon 85 the peripheries of the four running-wheels, and the motion of its spindle is communicated by friction to the running-wheels, which thus become driving-wheels and cause the truck to move over the floor.

90 It will be noticed that between the axles the frame is arched upward, so as to come opposite the ends of the top-spindle as it lies in the angles of the running-wheels, thereby confining the spindle against endwise motion. 95 When run down, the motor may be removed, fresh velocity imparted to it, and then replaced on the truck as at first.

The motor may be recharged in another way—namely, by pushing or pulling the truck over the floor—the motion of the running-wheels imparting velocity to the motor.

5 When the pushing or pulling ceases, the truck will continue to advance until the motor is again run down, or directly after pushing the truck the motor may be removed by taking hold of the handle. When thus 10 removed, it may be set upon its end on the floor, when it will spin as a top. Instead of lifting the top out it may be caused to spin on the floor by simply upsetting the vehicle. The relation of the truck and the motor is 15 thus reciprocal. Either may drive the other.

As represented in Figs. 1, 2, and 3, W W are the wheels of the top; S, its spindle; H, its handle; s, the string to spin it by. The handle is of a slightly different form from that illustrated in the previous application referred to above, but it is the same in principle. We consider this form better adapted to the purpose in hand.

A train of cars or other toys may be hitched 25 to one of the hooks R and the motor will pull them like a locomotive, or the toy may be pulled over the floor by a string attached to one of the hooks. In either case the rod will be pulled so that one of the hooks R will enter 30 one of the grooves g in the end of the frame, as shown at the left-hand end in Figs. 1 and 3. These grooves are to prevent the rod from turning over, as it might otherwise occasionally do in case the strain of pulling 35 should come upwardly on the hooks.

We prefer to use the top for a motor and to have it removable from the truck because this gives a greater variety of ways of using the toy. A single wheel will do, however, 40 and it may be confined to the truck by making flanges f f to project over the ends of its shaft, as shown in Fig. 4.

If desired, a hole h may be made through the shaft to permit the attachment of a string 45 to impart velocity to the wheel.

With a single wheel it is desirable to make some minor changes in the construction—as, for instance, substituting the two rods R' R' 50 for the single rod R and making different provision for attaching cars or other toys.

The construction of the toy may be varied considerably without departing from the spirit of our invention. For instance, a top with two wheels is not necessary. A one-wheeled top would do, but we prefer two wheels because it makes a more symmetrical construction and distributes the weight more uniformly. Again, it is not necessary that the two pairs of running-wheels should overlap 55 each other, for if the shaft of the inertia-wheel be large enough in diameter the adjacent wheels may lie in the same plane.

Having now described our invention, what we claim as new, and desire to secure by Letters Patent, is—

1. In a toy vehicle; the combination of one or more axles each having a pair of running-wheels located near its outer ends and having a shoulder back of each running-wheel to prevent it from moving inwardly on the axle; a frame to pass outside of the running-wheels and having notches on its under side to pass over the projecting ends of the axles and form bearings therefor; a rod passing longitudinally along the vehicle, between the wheels and under the axles, and having its ends supported on the transverse members of the frame; means to prevent said rod from becoming accidentally displaced; the whole construction being such that the rod prevents the frame from lifting off of the axles, while the frame confines both wheels and axles against endwise motion; substantially as specified. 70 75 80

2. In a toy vehicle, one or more axles with their running-wheels, a frame having notches on its under side to fit over the axles and form bearings therefor, a rod passing longitudinally along the vehicle between the wheels and under the axles and having its ends supported by the frame, means to prevent said rod from being accidentally displaced, all in combination substantially in the manner and for the purpose specified. 85 90

3. In a toy wagon, two pairs of wheels with their axles; a frame having on the under side thereof four notches to fit over the axles and form bearings therefor; a rod passing longitudinally along the wagon, below the wheels and under the axles and over the transverse members of the frame at either end of the wagon; notches in said transverse end pieces of the frame to receive the said rod and prevent it from moving laterally; the ends of the rod bent downwardly; all in combination substantially in the manner and for the purpose specified. 95 100 105

4. In a toy wagon, two axles each having a pair of wheels thereon; a frame having on its underside four notches to fit over the axles and form bearings therefor; a rod passing longitudinally along the wagon, between the wheels and under the axles, the two ends of the rod resting on the transverse members of the frame at either end of the wagon; means to prevent said rod from accidentally coming out of place; all in combination substantially in the manner and for the purpose specified. 110 115

5. In a locomotive toy, four running-wheels arranged in two pairs near together and in such manner that the adjacent wheels form an angle in which a shaft may lie; an inertia-wheel fixed to a shaft, said shaft lying in the angle formed by the adjacent pairs of running-wheels; the whole in combination and arranged to operate substantially in the manner and for the purpose specified. 120 125

6. A locomotive toy consisting of a vehicle having four running-wheels arranged in two pairs near together and in such manner that 130

the adjacent wheels form an angle in which a shaft may lie; an inertia-wheel fixed to a shaft and independent of the vehicle; on the shaft of the inertia-wheel a handle loosely mounted to enable the wheel to be held in the hand while velocity is imparted thereto and also to enable the live wheel to be placed upon the vehicle with its shaft resting in the angle formed by the four running-wheels,

the inertia-wheel then acting as a motor and causing the vehicle to move ahead substantially as specified.
